APPARATUS FOR GASIFICATION OF WOOD

Clarence E. Jenkins, Keene, N. H.

Application November 2, 1945, Serial No. 626,258

12 Claims. (Cl. 48—76)

1

This invention relates to the generation of gas from wood and wood substances such as wood chips, fragments, pieces, or particles, including stalks and corn cobs, although harder wood substances are preferred.

Inasmuch as the invention finds its maximum usefulness on woods commonly used as fuels, it will be specifically described in connection with the generation of gas from wood chips, but this is by way of illustration.

It is of course well known in the art to generate fuel gases from charcoal, and generally from various wood substances, but units heretofore constructed for use with natural wood, as distinguished from charcoal, produce distillates or condensable vapors which are apt to detrimentally affect or choke the producer, or the gas pipes and burners, or require elaborate gas cleaning means that must themselves be periodically cleaned. All such apparatus is undesirable, especially for small units designed for home use in regions where wood is plentiful and other fuels are costly, inaccessible, or not readily available.

It is an object of the present invention to provide a producer of relatively cheap and simple construction, especially applicable, though not limited to, sizes for domestic use, which do not tend to become fouled or clogged with condensates and distillates, and which have a relatively high gas production per volume of fuel used.

To this end my invention provides a producer and method of operating the same wherein the wood, periodically charged into the producer, is progressively distilled and reduced to charcoal and then to ash, under conditions which destroy or crack the volatile condensable distillates, and tars, resulting in the production of a gas which is relatively clean and dry. The unit and its method of operation tend to provide a vortex or swirl in the air inlet zone through which the effluent gases pass in a unique and effective manner.

My invention may be more fully understood by reference to the accompanying drawings in which:

Fig. 1 is a vertical section through a producer embodying my invention;

Fig. 2 is a transverse section in the plane of line II—II of Fig. 1;

Fig. 3 is a fragmentary section of the lower part of the producer opened for the discharge of ash;

Fig. 4 is a fragmentary bottom plan view on an enlarged scale of a portion of the inlet air diffuser, and

2

Fig. 5 is a fragmentary vertical section in the plane of line V—V of Fig. 4.

In the drawings 2 designates a cylindrical metal shell, which typically may be from 12 to 16 inches in diameter. It is provided with a top cover 3 hung from a hinged clamping bar 4, there being a bolt and wing nut assembly 5 at one end of this bar for holding the cover down and applying pressure to it; the hinge for the bar being designated at 6. The cover should make a tight seal with the body under normal operating conditions, but it may be opened from time to time to charge additional wood into the retort or shell. The lower portion of the shell is surrounded by a thermal insulating jacket 7.

At the bottom of the shell 2 there are spaced metal plates 8 and 8a with intervening thermal insulation 9, and passing through the center of this bottom structure is a metal ash discharge cone 10 having a perforated top 11 through which ashes may fall. The perforated top 11 also constitutes a spider or support for a vertical central shaft 12, the lower portion of which is threaded, and which has fixed to its top a curved agitator or ash rake 13, which as shown in Fig. 2 has radially extending curved arms which serve, when the rake is rotated in a clockwise direction, to move the ashes encountered thereby toward the center perforate area.

On the lower end of the shaft is a fixed collar 14 with ratchet teeth 15 on its upper end, this collar being keyed to the shaft. Threaded on the shaft between the collar and the upper end of the shaft is a hub or nut element 16 with ratchet teeth 17 on its lower end and with a truncated conical peripheral surface 18 from which extend downwardly and outwardly projecting spokes 19 that join to a rim or ring 20.

When the threaded collar is in the upper position shown in Fig. 1, its conical surface makes a sealing contact with the lower edge of the ash discharge cone 10, but using the rim or ring 20 as a hard wheel, the nut may be screwed down on the shaft until its ratchet teeth mesh with those on the collar 14 (see Fig. 3) so that the ash agitator or rake may then be rotated. At this time the bottom of the cone 10 is open, so that the ashes will fall out, but they fall between the spokes 19 and not onto the hands of the operator who is holding the ring 20. There is thus provided a unique seal and ash remover that imposes on the operator a minimum of conscious effort in opening the ash drop, shaking the ashes and then closing it.

Secured to the shell 2 near the top is a fitting

21 into which is entered and from which is hung a curved gas off-take pipe 22, the pipe curving from the fitting outwardly and downwardly, its length below the curve being substantially coincident with the vertical axis of the shell. There is a pipe 23 connected to the fitting 21 outside the producer, this pipe having a T connection 24 therein with a waste pipe 25 leading therefrom, there being a valve 26 in this pipe. There is also a service pipe 27 connected into the T, 10 the service pipe having a valve 28 therein.

Concentrically positioned about the vertical lower portion of the gas off-take pipe 22 is an air inlet pipe 29 having a radial connection 30 at its top which connects to a fitting 31 on the shell, giving increased rigidity to the axial concentric pipe arrangement. Also, with the arrangement the off-take pipe and air inlet duct are in heat exchanging relation. The lower end of the air duct or pipe 29 opens into a distributor 32, this distributor having an upper plate or disk 33, a sealing ring or flange 34, a bottom plate 35, with a wind chamber 36 between the two plates. The gas off-take pipe passes through the wind chamber and opens through the bottom plate 35. Near the periphery of the distributor the bottom plate has small holes 37 bored diagonally therethrough, all of the holes sloping in the same direction, so that the air discharged from the openings blows downwardly and tangentially to create a cyclone or vortex under the distributor.

The distributor is spaced above the bottom of the shell several inches. It is considerably smaller in diameter than the shell so that fuel can feed down past it, but should be large enough to avoid a relatively cold area being present in the fuel bed remote from the distributor.

There is an air supply pipe 38 connected to the fitting 31 outside the generator, this pipe connecting to a small power driven blower 39. There 40 is a T connection in pipe 38 with a down leg connected to flexible or resilient tube 40, which for example may be copper tubing, there being a hand valve 41 at the top of this tube where it joins the T. On the lower end of the tubing there is an igniter comprising a tube 42 slidably entered and sealed in an opening through the shell of the generator at a level just below the distributor. It has a removable screw-plug 43 at its outer end. By reason of the limited flexibility or resilience of the air supply tubing 40 the igniter may normally assume the position shown in Fig. 1, but to start the producer, it is pushed in to the dotted line position in which the inner end of the igniter is then adjacent the lower face of the distributor.

The operation and preferred method of operating may now be followed. Assume that there is no charge in the shell and the generator is just being put into use. Charcoal is first charged into the generator to about the level of the distributor. Charcoal is preferably used in starting as it gives the quickest results and after once being put into use, there will always normally be charcoal in this zone. Wood chips are then charged in above the charcoal until the generator is full and the lid is then clamped down.

When the charcoal is first charged into the generator, it will be obstructed at the center by the distributor disk and will repose in such a manner as to leave an inverted conical space below the distributor. This is indicated at A in Fig. 1. The igniter tube 42 is pushed in to the dotted line position of Fig. 1 so that its inner end just enters the chamber under the distrib-

utor. The screw plug 43 is removed, and a lighted taper is inserted.

With the blower 39 in operation, valve 41 is opened and plug 43 is put back in the end of the igniter tube. There will be sufficient back pressure in the distributor so that much of the air will blow through the igniter tube, and the fuel surrounding the inverted conical space will quickly come to incandescence.

During this starting period, service line valve 28 is closed and vent line valve 26 is opened, so that the air and starting gases are vented. Ash drop cone 18 is of course closed.

After the combustion has been well started, 15 valve 41 is closed, shutting off air to the igniter tube, which is then pulled back to its normal position. All of the incoming air then enters the generator through the inclined holes 37 of the distributor, creating a whirl or vortex of air in 20 the space A and forming a zone of intense heat in the wall of fuel immediately surrounding this space. Only the outermost air in this swirl is contacting the fuel, and as oxidation occurs, the CO₂ gas that is formed passes out through the 25 fuel bed and in so doing is converted to CO. It moves out to a cooler portion of the fuel mass. Some of it swirls downwardly and inwardly, rising through the center of the vortex and passes out pipe 22. Other portions of the gas rise 30 through the fuel bed, driving out volatiles and causing the wood chips just above the combustion zone to be reduced to charcoal. The gases thus rising through the chips and which are driven out of the chips form an eddy, apparently from the sides of the retort and downwardly near the center into the hottest part of the fuel bed, where the volatiles and gases burn upon contact with the incoming air. Only gases that have passed through the hot combustion zone and then swirl downwardly and inwardly can rise through the vortex in the space A and be carried off.

Pressures in the retort are slightly above atmospheric pressure to cause the gas to flow out the off-take pipe. The gas, after a period of 45 operation is mostly CO, H, and N, although there is some CO₂, CH₄, some water vapor, and a trace of other condensates, but no tarry masses to clog the apparatus or required cleaning is needed. Preferably there is some vapor trap, not shown, 50 in the service line to catch the small amount of water vapor and condensates that are formed. After the producer has been operating to make satisfactory gas, valve 26 to the waste line is closed and service pipe valve 28 is opened.

55 Thereafter the generator continues to operate. The charcoal is gradually consumed to ash and drops down and new charcoal from above replaces it, and the cycle of distillation and producing charcoal continues. From time to time the producer may be opened to charge in fresh fuel and from time to time ashes are shaken from the bottom.

In operation the generator produces gas of 60 good quality at a satisfactory rate and at high efficiency, the caloric value of the gas being high compared to the theoretical caloric content of the wood. It is observed, as the producer operates, that the space A does not remain uniformly centered under the off-take pipe, but tends to gyrate about the central axis, which is a highly desirable condition.

The number of air holes in the distributor, the 65 diameter of the distributor with reference to the diameter of the shell, and similar factors are

determined by experiment for each particular size of unit, but the relative proportions here shown and described have been found to be satisfactory.

While I have shown and described a preferred embodiment of my invention, it will be understood that various changes and modifications may be made in this construction within the spirit of my invention.

I claim:

1. A wood gas producer comprising a fuel holder, a hollow disk-like member centrally and horizontally positioned in the fuel holder spaced above the bottom thereof, said disk-like member having a chamber on the interior thereof and having inclined openings through the bottom face thereof near its periphery whereby air discharged from the chamber through the openings is caused to swirl in the space under the disk-like member, means for supplying air under pressure to said chamber, and means passing through the center of the disk-like member for removing gases from the producer.

2. A wood gas producer comprising a fuel holder, a hollow disk-like member centrally and horizontally positioned in the fuel holder spaced above the bottom thereof, said disk-like member having a chamber on the interior thereof and having inclined openings through the bottom face thereof near its periphery whereby air discharged from the chamber through the openings is caused to swirl in the space under the disk-like member, means for supplying air under pressure to said chamber, and means passing through the center of the disk-like member for removing gases from the producer, said means including an off-take pipe, said air supply means including a duct surrounding the off-take pipe.

3. A wood gas producer comprising a fuel holder, a hollow disk-like member centrally and horizontally positioned in the fuel holder spaced above the bottom thereof, said disk-like member having a chamber on the interior thereof and having inclined openings through the bottom face thereof near its periphery whereby air discharged from the chamber through the openings is caused to swirl in the space under the disk-like member, means for supplying air under pressure to said chamber, means passing through the center of the disk-like member for removing gases from the producer, a radially movable igniter tube passing through the holder and sealed therein adapted to have its terminal project from a point adjacent the wall of the holder to a point adjacent the under side of the periphery of said member, and means for selectively causing air under pressure to circulate through the igniter tube.

4. A wood gas producer comprising a fuel holder having a bottom therein, the bottom having a central ash discharge opening therein, a shaft passing through said opening with an agitator on the upper end thereof, the lower portion of the shaft being threaded, a conical member threaded on the shaft movable upwardly to close the ash discharge opening, and means on the lower part of the shaft for cooperation with said conical member when the conical member is screwed down on the shaft for causing the shaft to rotate with the conical member.

5. A wood gas producer comprising a hollow, cylindrical, vertical fuel holder, a distributor element in the fuel holder near the bottom thereof but spaced above the bottom, said distributor being of disk-like form and having a diameter

substantially less than the interior diameter of the holder whereby fuel in the holder may gravitate downwardly past the distributor and repose at an angle under the distributor to form an inverted generally conical pocket, means on the under face of the distributor for discharging air into the pocket in a tangential direction to produce a swirl of air, and means for removing gas from the region of the center of the pocket.

10 6. A gas generator of the class described comprising a casing having a vertical chamber therein through which fuel may move by gravity, an air inlet distributor in the chamber spaced from the walls thereof and spaced above the bottom thereof, the distributor having openings therein through which air may be projected into the space beneath it in a downward and tangential direction, means for supplying inlet air to the distributor, the distributor being constructed to obstruct the downward feeding of fuel in the portion of the chamber immediately above it whereby to form an open space under the distributor, and means opening into said space for removing gases therefrom.

25 7. A gas generator of the class described comprising a casing having a vertical chamber therein through which fuel may move by gravity, an air inlet distributor in the chamber spaced from the walls thereof and spaced above the bottom thereof, the distributor having openings therein through which air may be projected into the space beneath it in a downward and tangential direction, means for supplying inlet air to the distributor, the distributor being constructed to obstruct the downward feeding of fuel in the portion of the chamber immediately above it whereby to form an open space under the distributor, and means opening into said space for removing gases therefrom, there being concentric inlet and outlet pipes for the air and gases respectively which are in heat exchanging relation.

30 8. A wood gas producer comprising a fuel holder, means including a horizontally disposed flange suspended in the holder for creating a substantially centrally located pocket in the lower portion of the fuel mass in the holder when the holder is charged with fuel, said flange having an air supply chamber therein, a conduit connecting said chamber with a source of air supply, said flange having a plurality of peripheral openings with their upper ends in communication with said air supply chamber and their lower ends terminating on the underside of said flange, said openings being so constructed and arranged as to create a downwardly projected swirl of air in said pocket rotating about the central axis of the holder, and gas withdrawal means positioned substantially centrally of the underside of said flange for removing gas from the central portion of the swirl of air.

35 9. A wood gas producer comprising a fuel holder, means including a horizontally disposed flange suspended in the holder for creating a substantially centrally located pocket in the lower portion of the fuel mass in the holder when the holder is charged with fuel, said flange having an air supply chamber therein, a conduit connecting said chamber with a source of air supply, said flange having a plurality of peripheral openings with their upper ends in communication with said air supply chamber and their lower ends terminating on the underside of said flange, said openings being so constructed

and arranged as to create a downwardly projected swirl of air in said pocket rotating about the central axis of the holder, and gas withdrawal means positioned substantially centrally of the underside of said flange for removing gas from the central portion of the swirl of air, said withdrawal means comprising a conduit extending upwardly and axially through said flange.

10. A wood gas producer comprising a fuel holder, means including a horizontally disposed flange suspended in the holder for creating a substantially centrally located pocket in the lower portion of the fuel mass in the holder when the holder is charged with fuel, said flange having an air supply chamber therein, a conduit connecting said chamber with a source of air supply, said flange having a plurality of peripheral openings with their upper ends in communication with said air supply chamber and their lower ends terminating on the underside of said flange, said openings being so constructed and arranged as to create a downwardly projected swirl of air in said pocket rotating about the central axis of the holder, gas withdrawal means positioned substantially centrally of the underside of said flange for removing gas from the central portion of the swirl of air, and an igniter having its inner end movable toward and away from said pocket.

11. A wood gas producer comprising a fuel holder, means including a horizontally disposed flange suspended in the holder for creating a substantially centrally located pocket in the lower portion of the fuel mass in the holder when the holder is charged with fuel, said flange having an air supply chamber therein, a conduit connecting said chamber with a source of air supply, said flange having a plurality of peripheral openings with their upper ends in communication with said air supply chamber and their lower ends terminating on the underside of said flange, said openings being so constructed and arranged as to create a downwardly projected swirl of air in said pocket rotating about the central axis of the holder, gas withdrawal means positioned substantially centrally of the underside of said flange for removing gas from the central portion of the swirl of air, and an igniter having its inner end movable toward and away from said pocket.

toward and away from said pocket, said igniter comprising a tube having a movable plug at its outer end and means for selectively forcing air into the igniter.

- 5 12. A gas generator comprising a shell having a fuel holding chamber therein, a distributor in the shell for supplying air to the interior of the chamber, said distributor comprising a horizontally disposed flange spaced from the bottom and sides of the shell, the distributor flange having an air supply chamber therein and having peripheral openings with their upper ends in communication with said supply chamber and their lower ends terminating on the underside of the flange, said openings being so constructed and arranged as to form a swirl of air concentrically within the shell immediately below said flange and about the vertical axis of the shell, and gas withdrawal means positioned substantially centrally of the underside of said flange for removing gases from the fuel chamber at the top center of said swirl.
